UNITED STATES PATENT OFFICE.

RANDOLPH CROMPTON, OF WORCESTER, MASSACHUSETTS.

DESIGN FOR A DROP FOR WARP-STOP-MOTION MACHINES.

SPECIFICATION forming part of Design No. 31,259, dated July 18, 1899.

Application filed June 16, 1899. Serial No. 720,864. Term of patent 14 years.

To all whom it may concern:

Be it known that I, RANDOLPH CROMPTON, a citizen of the United States, residing at Worcester, in the county of Worcester and State of Massachusetts, have invented and produced a new and original Design for a Drop for Warp-Stop-Motion Machines, of which the following is a specification, reference being had to the accompanying drawings, forming a part thereof.

Referring to the drawings, Figure 1 is a flat side or face view of a drop of my design; and Fig. 2 is an edge view of the same, looking in the direction of arrow *a*, Fig. 1.

As shown in the drawings, my drop 1 is of elongated form, with parallel sides or edges, except at one portion of the drop, near the lower end thereof, and with curved ends. The drop 1 has an elongated slot or opening 2 in the upper part thereof and a circular opening or perforation 3 through the central portion thereof below the said elongated opening 2.

At the lower end of the drop, on one edge thereof, is an angular notch or recess 4, the 25 sides of which are formed by straight lines, the longer straight line 4' extending downwardly and inwardly and the short straight line 4" extending upwardly and inwardly and at an angle of forty-five degrees to the line 30 4' to form the angular notch 4.

The leading feature of my design is the elongated slot or opening 2 in one end of the drop device, the circular opening or eye 3 in the central portion, and the angular notch or recess 4 in one edge at the other end thereof.

What I claim is—

The design for a drop for warp-stop-motion machines, substantially as herein shown and described.

RANDOLPH CROMPTON.
